UNITED STATES PATENT OFFICE.

JOHN WESLEY STEWART, OF TYRONE, PENNSYLVANIA.

AUTOMATIC LUBRICATOR FOR SLIDE-VALVES.

SPECIFICATION forming part of Letters Patent No. 677,901, dated July 9, 1901.

Application filed September 12, 1900. Serial No. 29,832. (No model.)

To all whom it may concern:

Be it known that I, JOHN WESLEY STEWART, a citizen of the United States, residing at Tyrone, in the county of Blair and State of Pennsylvania, have invented a new and useful 55 Automatic Lubricator for Slide-Valves, of which the following is a specification.

The invention relates to improvements in automatic lubricators for slide-valves.

10 The object of the present invention is to improve the construction of automatic lubricators for slide-valves and to provide a simple and comparatively inexpensive one designed to be applied to the steam-chests of 60 locomotives and other engines for supplying a lubricant to the same and adapted to relieve the oil-inlet of steam-pressure, to obviate the necessity of driving the lubricant into the steam-chest, and to enable any ordinary 65 oil-cup or analogous lubricating device to be employed.

15 The invention consists in the construction and novel combination and arrangement of parts hereinafter fully described, illustrated 70 in the accompanying drawings, and pointed out in the claims hereto appended.

20 In the drawings, Figure 1 is a longitudinal 75 sectional view of a steam-chest provided with an automatic lubricator constructed in accordance with this invention. Fig. 2 is a detail sectional view illustrating the construction of the automatic lubricator. Fig. 3 is a plan view of the automatic lubricator. Fig. 4 is a detail perspective view of the tubular 80 valve with its depending fork.

25 Like numerals of reference designate corresponding parts in all the figures of the drawings.

30 1 designates a tubular valve of cylindrical 85 form arranged within a cylindrical casing 2 at the top of a steam-chest 3, which is provided with a slide-valve 4 of any ordinary construction. The slide-valve and the steam-chest are provided with the usual ports, and 90 45 the cylindrical casing 2 of the tubular valve is mounted within an approximately triangular support or bracket 5, designed to be secured to the top of the steam-chest, above the center thereof, as illustrated in Fig. 1 of the 95 accompanying drawings. The approximately 100

triangular bracket or support is composed of approximately triangular end walls 6 and inclined sides 7, and it is provided at its ends with flanges 8, which are perforated for the reception of suitable fastening devices for securing the bracket to the top of the steam-chest.

35 The tubular valve, which is adapted to turn within the cylindrical casing, is provided with openings or ports 9 and 10, and it has a depending fork 11, rigidly connected with it at one end and straddling a grooved roller or wheel 12 of the slide-valve 4. The fork is arranged in a vertical position, as illustrated in Fig. 1 of the accompanying drawings, when 65 the slide-valve is at the center of its stroke, and the grooved wheel or roller 12 is mounted on a suitable pivot or journal at the center of the stroke of the slide-valve or at a point midway between the ports of the same, so that it 70 will lie directly beneath the lubricator when the slide-valve is at the center of its stroke. When the slide-valve is reciprocated, the fork will be oscillated and will oscillate the tubular valve. When the fork is at one end of the 75 stroke of the slide-valve, the port or opening 9 at the bottom of the tubular valve 1 registers with a lower discharge opening or port 13 at the bottom of the casing, and as the slide-valve is reciprocated and the fork is carried 80 toward the other end of the stroke of the said slide-valve the lower port 13 for the discharge of oil will be closed to shut off the steam-pressure from the interior of the valve, and the opening or port 10 of the latter will be first 85 carried into register with a relief-port 14 to permit the steam to escape and to reduce the pressure within the valve, so that oil will flow into the same when the upper port or opening registers with an oil-inlet opening 15 of 90 the top of the valve-casing. The oil-inlet opening 15 at the top of the valve-casing is designed to communicate with the oil-pipe 16 of an oil cup or holder 17, and it will be readily apparent that as the steam-pressure is removed from the interior of the valve when the inlet-port at the lower end of the oil-tube is open the lubricant will be permitted to flow freely into the valve and will not require any power to force it into the same; and an ordi- 95 100

nary oil-cup or lubricant-holder may be employed. On the return stroke of the slide-valve the oil-inlet opening is first closed and the relief-port is again uncovered and then 5 closed before the lower opening or port 9 registers with the oil-discharge opening or port 13 at the bottom of the valve-casing. When 10 the discharge opening or port 13 at the bottom of the casing is open, the relief-port and the oil-inlet port or opening at the top of the valve-casing are closed or covered, so that the steam is not permitted to escape from the same and the lubricant-holder is relieved of the steam-pressure. As the steam will enter the 15 valve, the pressure on the interior of the same will be equal to the pressure within the steam-chest and the lubricant will be permitted to flow freely into the same.

The valves are designed to be constructed 20 right and left hand to correspond with the steam-chest of a locomotive, and they are adapted to be applied to the steam-chest of various other forms of engines. The top of the steam-chest is provided with an opening 25 or port 18, which communicates with the relief-port; but this may consist of a continuous passage, and the outer end of the relief-port is designed to be plugged with cotton or any other suitable material which will permit 30 the escape of the steam and at the same time exclude dust and other foreign matter from the valve. This porous filling or plug 19 may be arranged as illustrated in Fig. 2 of the accompanying drawings, or any other 35 suitable means may be provided to effect this result.

The valve is adapted to feed the lubricant automatically to the steam-chest while the slide-valve is in motion, and it will automatically 40 shut off the flow of the lubricant when the engine is stopped, so that there will be no waste of oil.

One end of the cylindrical casing 2 is open and the other end is provided with an aperture 45 for the reception of a stem 20, projecting centrally from the adjacent end of the valve 1 and provided with a perforation for the reception of a split key 21 or other suitable fastening device for retaining the valve 50 in the casing; but any other suitable means may be employed for effecting this result, and the bracket or support may be cast solid or otherwise formed to secure the necessary strength, and I desire it to be understood 55 that various other changes in the form, proportion, size, and the minor details of construction within the scope of the appended claims may be resorted to without departing from the spirit or sacrificing any of the ad- 60 vantages of this invention.

It will be seen that the automatic lubricator is exceedingly simple and inexpensive in construction, that it possesses great strength and durability, and that it is adapted to be 65 readily applied to the steam-chests of loco-

motives and various other forms of engines whether stationary or movable. It will also be apparent that the automatic lubricator relieves the oil-inlet opening of steam-pressure to obviate the necessity of forcing the oil into 70 the steam-chest and to enable an oil-cup or any other form of lubricant-holder to be employed and that the relief-port permits the escape of steam to reduce the pressure in the automatic lubricator before the oil-inlet opening is uncovered. Furthermore, it will be apparent that the fabric plug of the relief-port will permit the ready escape of steam and at the same time exclude dirt and other foreign matter from the lubricator and the 80 steam-chest.

What I claim is—

1. In a device of the class described, the combination of a lubricant-holder, a valve-casing designed to be located within a steam-chest and provided with oil inlet and discharge openings and having a relief-port, the oil-inlet opening communicating with the lubricant-holder, and a valve mounted within the valve-casing and adapted to uncover the 90 openings and the relief-port of the valve-casing successively, whereby the oil-inlet opening is relieved of steam-pressure, substantially as and for the purpose described.

2. In a device of the class described, the 95 combination of a valve-casing designed to be located within a steam-chest and provided with oil inlet and discharge openings and having a relief-port, and a valve arranged to successively uncover the openings and the relief-port of the valve-casing, whereby the oil-inlet is relieved of steam-pressure, substantially as and for the purpose described.

3. In a device of the class described, the combination of a valve-casing designed to be 105 mounted within a steam-chest and provided with oil inlet and discharge openings and having a relief-port, a valve arranged within the valve-casing, and means for connecting the valve with a slide-valve, substantially as 110 described.

4. In a device of the class described, the combination of a lubricant-holder, a valve-casing designed to be mounted within a steam-chest and communicating with the lubricant-holder, an oscillatory valve mounted within the valve-casing, and an oscillating member 115 fixed to the oscillatory valve and designed to be connected with a slide-valve, substantially as described.

5. In a device of the class described, the combination of a valve-casing designed to be located within a steam-chest, a tubular oscillatory valve provided with a depending fork, and a roller or wheel designed to be mounted 125 on a slide-valve and receiving the fork, substantially as described.

6. In a device of the class described, the combination of a valve-casing designed to be mounted within a steam-chest and having 130

oil inlet and discharge openings and provided with a relief-port communicating with the atmosphere, a valve arranged to successively uncover the openings and the port, and a 5 porous plug adapted to permit the escape of steam and to prevent foreign matter from entering the valve, substantially as described.

In testimony that I claim the foregoing as my own I have hereto affixed my signature in the presence of two witnesses.

JOHN WESLEY STEWART.
